BRIDLE BIT

Filed May 22, 1922

FIG. 1.

FIG. 2.

FIG. 3.

Inventor

Henry A. Oelkers

By Watson E. Coleman
Attorney

UNITED STATES PATENT OFFICE.

HENRY A. OELKERS, OF MAZEPPA, MINNESOTA.

BRIDLE BIT.

Application filed May 22, 1922. Serial No. 562,734.

To all whom it may concern:

Be it known that I, HENRY A. OELKERS, a citizen of the United States, residing at Mazeppa, in the county of Wabasha and State of Minnesota, have invented certain new and useful Improvements in Bridle Bits, of which the following is a specification, reference being had to the accompanying drawings.

10 This invention relates to bridle bits, and has for its object to provide a bridle bit capable of correcting the improper position of the head of an animal.

15 It is another object of the invention to provide a bit of this character, which permits the animal to be driven in the usual manner, and yet is provided with means for causing the animal to hold its head straight to carry the load or draft evenly.

20 It is a further object of the invention to provide a bridle bit of this character including a sectional mouth piece having projecting from one of the sections a member arranged to cause the animal to turn its head in the direction of travel without interfering with the operation of the bit when the animal is turned by the driver to either side to change the direction of travel.

25 With these and other objects in view, the invention consists in the improved construction and arrangement of parts to be herein-after more particularly described, fully claimed and illustrated in the accompanying drawings, in which—

30 Figure 1 is a perspective view of a bridle bit constructed in accordance with an embodiment of the invention;

Figure 2 is a top plan view; and

35 Figure 3 is a detailed plan view of one section of the bit.

40 It is a well known fact that it is rather difficult to break an animal, such as a horse or colt, of the habit of turning their heads so far to one side as to cause the load or draft to be on one shoulder, thus overdeveloping the shoulder and causing sweating. To correct this condition and at the same time provide a bridle bit that may be used in the well known manner there is provided a mouth piece 5 including sections 6 and 7, the section 6 consisting of a length of material having an eye 8 formed at one end thereof, the opposite end portion being extended back upon the portion 9 to provide an

eye 10. The eye 8 of the section 6 is disposed substantially in a plane parallel to the plane of the eye 10.

55 The section 7 of the mouth piece consists of a length of material having an eye 11 formed in one end thereof adapted to receive a portion of the section 7 forming the eye 8 so as to provide a jointed or movable bit. This connection is of conventional formation. The outer end portion 12 of the section 7 is extended at right angles to the end portion 13 of said section to provide a jaw arm, the diameter of the jaw being considerably smaller than the diameter of the end portion 13 of the section, the extremity of the jaw arm being curved upwardly. Projecting from the central portion of the section 7, or in other words, at the junction of the jaw arm 12 with the end portion 13, is an extension 14, said extension being formed integral with the central portion of the section and being also extended back upon the section 13 to provide an eye 15. The eyes 15 and 10 of the sections 7 and 6 are intended to receive the usual rein rings 16. These rings if desired may be provided with 60 cheek arms 17.

65 This bit is intended to be made in two styles, one with a jaw arm projecting from the left-hand section of the mouth piece and one with a jaw arm projecting from the right-hand section of the mouth piece. The purpose of this is to permit the bit having the right-hand jaw arm to be used on an animal which is in the habit of turning its head to the left, while the bit having the 70 arm on the left-hand side is intended to be used on an animal in the habit of turning its head to the right.

75 In the application of the bit, the bit is positioned so that the jaw arm 12 projects 95 backwardly along the jaw. When the driver pulls on the reins the mouth piece will break in the center in the usual manner and cause the jaw arm to pry the horse on its jaw, thereby forcing its head from the 100 side to a position directly front.

80 From the foregoing it will be readily seen that this invention provides a novel form of bridle bit capable of correcting the improper position of the head of an animal 105 in a short length of time, during which period the animal is caused to pull directly ahead so that the strain of the draft is ap-

plied to both shoulders. All of these features are possessed by a bridle bit which is durable and simple in construction.

What is claimed is:—

- 5 A bridle bit including a pair of mouth piece sections universally connected at their adjacent inner ends, and a rearwardly projecting arm rigid with the outer end of one of said sections and extending at right

angles thereto to provide an arm for engagement with the jaw of an animal, the outer ends of said sections having integral flat extensions return-bent to form bearings for rein rings, the other of said sections being devoid of arms or projections.

15

In testimony whereof I hereunto affix my signature.

HENRY A. OELKERS.
